UNITED STATES PATENT OFFICE.

JOHN CLEGHORN, OF DENVER, COLORADO, ASSIGNOR OF ONE-HALF TO
BERNHARD WILDERSIN, OF SAME PLACE.

RAILWAY SIGNALING APPARATUS.

SPECIFICATION forming part of Letters Patent No. 651,794, dated June 12, 1900.

Application filed March 20, 1900. Serial No. 9,433. (No model.)

To all whom it may concern:

Be it known that I, JOHN CLEGHORN, a citizen of the United States of America, residing at Denver, in the county of Arapahoe and State of Colorado, have invented certain new and useful Improvements in Railway Signaling Apparatus; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to improvements in railway signaling apparatus; and it consists of the features, arrangements, and combinations hereinafter described and claimed, all of which will be fully understood by reference to the accompanying drawings, in which is illustrated an embodiment thereof.

In the drawings, Figure 1 is a top or plan view of my improvement. Fig. 2 is a section taken on the line X X, Fig. 1, the parts being shown on a larger scale. Fig. 3 is a fragmentary section taken on the line Y Y, the parts being enlarged. Fig. 4 is an enlarged detail view of a feature of the apparatus. Fig. 5 is a section taken on the line Z Z, Fig. 4. Fig. 6 is a horizontal section taken through the signal-standard looking downward. Fig. 7 is an enlarged detail view of the locking mechanism.

Similar reference characters indicating corresponding parts in the views, let the numeral 5 designate the rails of the main track, which are provided at points suitably separated with short sections 6, hinged at 7 and having a limited degree of oscillation in a horizontal plane. Located adjacent each section 6 is a tongue 8, hinged at 9, its free or pivoted extremity being normally held in contact with the part 6 by means of a rod 10, passing through an opening in a guide-lug 12^a, fast on a stationary plate 12. This rod is provided with a collar 10^a. Between the collar 10^a and the guide-lug 12^a is located a coil-spring 13, which surrounds the rod. This rod is connected with the tongue at a point remote from the hinge-pin 9. The rail part 6 is provided with an extension-flange 6^a, through which the

hinge-pin 9 of the tongue passes, the latter being provided with a flange 8^a for the purpose. The flange 8^a of the rail part 6 rests on a bed-plate 14^a, connected with the rod 14. 55 The plate 14^a is provided with lugs 14^c, which engage the opposite edges of the part 6^a. The movable plate 14^a rests upon a stationary base-plate 15, secured to a base 16 by bolts 17. The plate 15 has a vertical projection 60 15^a, upon which rests a guard-plate 18, bolted to the web of the rail part 6. This guard-plate also rests upon a lug 14^c of the movable plate 14^a and keeps the space 19 free from obstructions, which otherwise might interfere 65 with the movement of the rod 14 and its connections. The rod 14 occupies a position at right angles to the direction of the track and extends beneath a guard-rail 22 on the opposite side of the track from the rail part 6. 70 The rod 14 is provided with a stiff spring or yielding part 14^d, which, as shown in the drawings, is formed integral with the rod. The function of this feature will be hereinafter explained. The extremity of the rod 14 remote 75 from the rail part 6 is pivotally connected with a triangular plate 20, fulcrumed at 21, and performs the function of a bell-crank lever. To the opposite diagonal corner of this plate is pivotally connected a rod 23, which extends 80 parallel with the direction of the track, its opposite extremity being connected with a similar lever-plate 20^a, fulcrumed at 21^a, its opposite diagonal corner being connected with a rod 24, extending at right angles to the rod 85 23. This rod 24 is connected with the lever-plate intermediate its extremities, one of which is connected with a V-shaped rail part 30, hinged at 31, its two arms or branches being respectively designated 30^a and 30^c. The 90 other extremity of the rod 24 is pivotally connected with a horizontal crank-arm 25, made fast to the vertical revoluble standard 26, provided with the signal 27. To the V-shaped rail part 30 is attached one extremity of a rod 95 35, which passes through a lug 12^a, formed on a stationary plate 12. (See Fig. 3.) Between this lug and the collar 35^a, formed on the rod, is located a coil-spring 13^a, which normally holds the part 30 in the position shown in full 100 lines in the drawings. This rod and spring construction is substantially the same as that

shown in Fig. 3 of the drawings. Hence it is not considered necessary to illustrate it in detail.

To the plate 20, at the point where the rod 5 is attached, is also connected one extremity of a link 28, whose opposite extremity is connected with one end of a transverse locking-bar 29, whose opposite end is connected with the rail part 6. This locking-bar is provided 10 with a bend or otherwise fashioned to form a recess or notch 29^a, adapted to receive a lug 32, formed on a stationary plate 33. As shown in the drawings, this bar is unlocked, the recess or notch 29 being disengaged from the 15 lug 32. The link 28 is composed of two parts A and B. (See Fig. 4.) The part A is forked at one extremity, as shown at A', and the arms of the fork embrace a stop B', fast on one extremity of the part B. The opposite 20 sides of this stop are grooved to receive the embracing fork-arms. (See Fig. 5.) To the extremities of the fork-arms are attached a stop A², provided with an opening, through which the link part B passes and within which 25 it slides freely. The link part B is also provided with a stop B². Between the stops A² and B² is located a coil-spring B³, which surrounds the link member B.

The mechanism already described is duplicated in order that the signal may be operated by a train traveling in either direction. Hence one set of mechanism having been described, the other set will not be set forth in detail.

35 The operation of the signaling mechanism will now be described.

A train moving in one direction will display the danger-signal to one approaching from the opposite direction in the following 40 manner: The wheels of the signaling train will engage the tongue 8 (of one set of signaling mechanism) from the inside and force the rail part 6 outward to the dotted-line position, bringing the tongue 8 into line with the main-track rail 5. This movement of the rail part 6 moves the rod 14 in the direction indicated by the arrow, turns the lever-plate 20 on its fulcrum, moves the rod 23 in the direction indicated by the arrow, and actuates 45 the lever-plate 20^a to throw the signal 27 in the direction indicated by the arrow through the agency of the rod 24 and the crank-arm 50 25. As the signal staff or standard is operated the V-shaped rail part 30 is shifted to 55 the dotted-line position, bringing the member 30^a into line with the main-track rail. Simultaneously with this operation the link 28 will be moved in the same direction as the rod 23 and the lock-bar shifted in the direction indicated by the arrow, causing the recess 29^a of the bar to engage the lug 32 of the plate 33, in which position the lock-bar is held through the instrumentality of the spring B³, thus locking the signal 27 in the changed 60 position and the rail part 30 in the dotted-line position. The operated signal may be 65 any desired distance, within reasonable lim-

its, from the mechanism first acted on by the operating-train. As the train passes along, its wheels engage the member 30^a of the operated rail-section 30 and force it outward to the full-line position, returning the signal to its normal position. Simultaneously with this operation the rod 23 and the link 28 are moved in the direction opposite that indicated 75 by the arrow, unlocking the bar 29 and shifting the lever-plate 20 to actuate the rod 29 in the direction opposite that indicated by the arrow, whereby the rail part 6 is thrown to the full-line position and the lock-bar shifted 80 to the normal position shown in the drawings. The function of the spring 14^d of the rod 14 is to allow the rod to yield slightly during the brief interval required to unlock the bar 29, since until this bar is unlocked the rail part 85 6 and the rod 14 cannot move bodily. The strength of this spring is such as to make the rod continuous or integral for all other purposes. After the train passes the operated signal, the flange of the wheel on one side 90 passes between the tongue 8 and the rail part 6 nearer the operated signal, throwing the tongue to the dotted-line position and compressing the spring 13^a, which as soon as the train passes returns the tongue to its normal 95 position through the agency of the rod 10. Hence the signaling mechanism is left in the same position as before, being ready for the next train.

Having thus described my invention, what I claim is—

1. A railway signaling apparatus comprising a movable rail part pivoted at one extremity, and normally in line with the main-track rail, a tongue occupying a position at an angle to the rail part and arranged to move therewith when the train is moving in one direction, said tongue being hinged to allow it to move independently of said rail part when the train is moving in the opposite direction, a rod connected with the rail part remote from its pivoted extremity, said rod being connected with the tongue adjacent its pivoted or hinged extremity, whereby the rail part and the tongue are made to oscillate as the rod reciprocates, a lever with which the opposite extremity of the rod is connected, another rod having one extremity connected with the same lever, another lever with which the opposite extremity of the last-named rod is connected, a signal, and another rod connected with the lever and with the signal, the parts being so arranged that the movement of the rail part operates the signal substantially as described.

2. A railway signaling apparatus comprising a movable rail part pivoted at one extremity, and normally in line with the main-track rail, a tongue occupying a position at an angle to the rail part and arranged to move in one direction, said tongue being hinged to allow it to move independently of the rail part when the train is moving in the opposite direction, a rod connected with the rail part

remote from its pivoted extremity, and connected with the tongue adjacent its pivoted or hinged extremity, whereby the rail part and the tongue are made to oscillate as the said rod moves back and forth, a lever with which the opposite extremity of the rod is connected, another rod having one extremity connected with the same lever, another lever with which the opposite extremity of the last-named rod is connected, a signal, another rod connected with the lever and with the signal, and a V-shaped rail part hinged at one extremity and having one arm normally in line with the main-track rail, the said V-shaped rail part being connected with the rod leading to the signal at a point remote from the pivoted end of the said rail part.

3. A railway signaling apparatus comprising a movable rail part pivoted at one extremity, and normally in line with the main-track rail, a tongue occupying a position at an angle to the rail part and arranged to move therewith when the train is moving in one direction, said tongue being hinged to allow it to move independently of the rail part when the train is moving in the opposite direction, a rod connected with the rail part remote from its pivoted extremity, and connected with the tongue adjacent its pivoted or hinged extremity, whereby the rail part and the tongue are made to oscillate as the said rod moves back and forth, a lever with which the opposite extremity of the rod is connected, another rod having one extremity connected with the same lever, another lever with which the opposite extremity of the last-named rod is connected, a signal, another rod connected with the lever and with the signal, a V-shaped rail part hinged at one extremity and having one arm normally in line with the main-track rail, the said V-shaped rail part being connected with the rod leading to the signal at a point remote from the pivoted end of the said rail part, and a spring-actuated rod connected with the V-shaped rail part and arranged to hold it in its normal position.

4. A railway signaling apparatus comprising a movable rail part pivoted at one extremity, normally in line with the main-track rail, a tongue occupying a position at an angle to

the rail part and arranged to move therewith when the train is moving in one direction, said tongue being hinged to allow it to move independently of said rail part when the train is moving in the opposite direction, a rod connected with the rail part remote from its pivoted extremity, said rod being connected with the tongue adjacent its pivoted or hinged extremity, whereby the rail part and the tongue are made to oscillate as the rod reciprocates, a lever with which the opposite extremity of the rod is connected, another rod having one extremity connected with the same lever, another lever with which the opposite extremity of the last-named rod is connected, a signal, and another rod connected with the lever and with the signal, and means for automatically locking the signal in the actuated position.

5. A railway signaling apparatus comprising a movable rail part pivoted at one extremity, and normally in line with the main-track rail, a tongue occupying a position at an angle to the rail part and arranged to move therewith when the train is moving in one direction, said tongue being hinged to allow it to move independently of said rail part when the train is moving in the opposite direction, a rod connected with the rail part remote from its pivoted extremity, said rod being connected with the tongue adjacent its pivoted or hinged extremity, whereby the rail part and the tongue are made to oscillate as the rod reciprocates, a lever with which the opposite extremity of the rod is connected, another rod having one extremity connected with the same lever, another lever with which the opposite extremity of the last-named rod is connected, a signal, and another rod connected with the lever and with the signal, means for automatically locking the signal in the actuated position, and means actuated by the train for unlocking the operated signal as the train passes the latter.

In testimony whereof I affix my signature in presence of two witnesses.

JOHN CLEGHORN.
